ART OF SEAMING FABRICS

Frank G. Weisbecker, Glenside, Pa., and William W. Fleming, Washington, D. C., assignors, by
meane assignments, to Hosiery Patents Incorporated, Lansdale, Pa., a corporation of Pennsylvania

Application November 15, 1939, Serial No. 304,594

27 Claims. (Cl. 66—187)

This invention relates to the art of seaming fabrics. More particularly, the invention relates to improvements in full-fashioned stockings and a method for seaming portions of a stocking blank in making such stockings.

The method of this invention is especially suitable for seaming the edge portion or portions at the tip or front end of a stocking blank toe. For purposes of illustration, the invention, therefore, will be described as applied to the joining of such portions of a full-fashioned stocking blank, but other applications of the invention will be readily understood from the description to follow.

Heretofore, the usual practice in manufacturing full-fashioned hosiery has been to produce the stocking blanks on knitting machines and to seam the stocking blank toe front edge portion in a so-called "looping" operation on a looping machine. This machine makes a chain stitch. It has also been a common practice to prevent runs in the stocking toe during removal of the stocking blank from a stocking blank knitting machine to a looping machine, by providing the stocking toe with a few extra courses, known as raveling courses. These raveling courses are formed on the machine which knits the toe fabric and are removed from the toe after the toe end edge to be seamed is supported in the looping machine for a looping operation.

There is a definite problem in seaming the stocking blank front toe edge which precludes the use of an ordinary sewing machine and which heretofore has required the use of the well-known looping machine. When the usual ravel courses are removed from the stocking toe fabric, a number of the wales in the toe fabric terminate in free loops at the front edge of the toe. In other words, the end or front edge of the toe is without a selvage, and particular care must be taken to so seam this stocking portion that the possibility of its edge loops being left free to start a stocking run is substantially eliminated. To avoid such runs or unraveling, it is necessary that each of the described free edge loops or terminal wale loops be secured, bound or locked in the seam for closing the toe end. The function of the conventional looping machine is to link each of these edge loops into a seam by means of a looping operation using a chain stitch.

The present invention is an important improvement over the described prior practice of "looping" the stocking blank toe front edge portions. The present invention shows how the front toe seam may be formed in a knitting operation. The invention also teaches how the front toe seam may be produced on the same machine which knits the stocking toe fabric. For example, the toe section of a knitted stocking blank may first be formed on a conventional footer knitting machine and then have its end or tip portions

provided with a seam by the same machine, all in a continuous operation. If a conventional single unit straight knitting machine is being used for producing both leg and foot portions of a stocking blank, the toe end portions may be united by the same knitting machine and without removal of the stocking blank therefrom. In this way, the invention eliminates the need for the prior art looping machines and reduces proportionately the necessary investment of a hosiery mill in knitting equipment. The operating expenses of a hosiery mill may also be materially reduced by practicing this invention, as it eliminates the need for looping machine operators and looper menders. The substantial economy, which may be secured by practice of this invention, is further apparent when it is considered that full-fashioned hosiery knitting mills have usually been equipped in the past with a looping machine for each footer knitting machine. This invention also permits a saving of time in the production of hosiery, as it does not require the prior time-consuming practice of removing the stocking blanks from the legger, footer, single unit or other knitting machine, which knits the stocking blanks or portions thereof, to looping machines for uniting the terminal wale loops of the stocking toe. The invention may, therefore, actually assist a hosiery mill in increasing its rate of production.

A number of other advantages are secured by the present invention. The invention may be practiced to provide a knitted seam which is smoother and flatter than the seam produced by a looping machine. A flat seam in a stocking toe is much more comfortable to a wearer than the raised seams produced by prior looping methods. The seams produced in accordance with this invention may have substantially the flat, smooth and pleasing appearance of plain silk stocking fabric and, in this respect, may be practically indistinguishable from the surrounding or adjacent knitted stocking areas. Another advantage of the present invention is that it provides a method whereby the usual raveling courses may be omitted and such waste of yarn may be avoided.

As ordinary yarn, of the character used in knitting a full-fashioned silk stocking blank, may also be used for seaming operations in the practice of this invention, the latter permits a further saving. The prior practice of "looping" seams for stockings requires special and relatively expensive yarn, generally termed "looping" yarn. This looping yarn is more expensive than the silk yarn usually forming stocking fabric. If such special looping yarn is not used in the looping operation, the stitches are apt to skip. The result would be so-called "open work," in which certain terminal wale loops at the toe edge are free to start a run in their respective wales.

The present invention also secures economy in yarn, as the usual toe raveling courses referred to above are now unnecessary.

It is, therefore, an object of this invention to simplify and improve the art of seaming fabrics, and particularly with respect to uniting the edges of knitted fabric.

Another object is to provide a novel method for seaming full-fashioned stocking blank edges.

Still another object is to provide a novel method of seaming the free terminal wale loops in the front edge of full-fashion stocking toes.

Another object is to provide fabric, and particularly the knitted toes of full-fashioned hosiery, with seams of improved character.

A further object is to secure a substantial saving with respect to the initial investment in hosiery mills, the operating expenses of such mills, and the manufacture of full-fashioned hosiery thereby.

A still further object is to provide a seaming method which will enable a full-fashioned hosiery knitting mill to increase its rate of production.

Other objects of this invention will be apparent from the following specification, the appended claims, and the accompanying drawings, wherein:

Figure 1 is an elevational side view of a full-fashioned stocking having its toe front or end portions provided with a seam in accordance with this invention.

Figure 2 is a front elevational view of the stocking toe in Figure 1 but without the usual sole seam, and shows the toe front edge portions united in accordance with this invention.

Figures 3 and 4 are perspective views (more or less diagrammatic) of portions of a full-fashioned hosiery, single unit straight knitting machine and portions of a stocking foot to illustrate progressive stages in the seaming of stocking toe edge portions according to this invention.

Figures 5 through 10 are diagrammatic views to illustrate one method of uniting the front edge portions of a stocking blank toe according to this invention, Figure 5 also being a front elevational view, on enlarged scale, of the machine parts and the stocking toe of Figure 3, and Figure 9 showing the stocking in the same stage of the described method as Figure 4.

Figure 11 is a diagrammatic detail view to show the relative arrangement of loops in a toe seam made in accordance with one embodiment of this invention.

Referring now to the drawings, Figure 1 shows a full-fashioned stocking in which the foot is made from a blank of the style or type shown in Figure 3. The illustrated stocking and blank include such usual parts as an instep portion 1, sole portions 2, heel portions 3, and a toe portion 6 having diamond points 5. The toe portion 6 and its diamond points 5 terminate at the front toe edge 10, as shown more clearly in Figure 5.

This invention provides the stocking toe with a knitted seam indicated at 8 in Figure 2. To form this toe seam 8, the outer toe edge portions 20 and 21 (see Figure 5) are, in effect, folded inwardly and united in the folded position to inner toe edge portions 22 and 23 respectively. The combined extent of the toe edge portions 20, 21, 22 and 23 is preferably the same as the length of the last course of the stocking foot blank, which last course usually consists of a plurality of free or terminal wale loops, one for each wale terminating at the toe edge 10.

This invention may be practiced in the manu-

facture of hosiery from the illustrated conventional stocking blank. This hosiery and its blank may be made on a conventional single unit straight knitting machine and a conventional heeler knitting machine according to known practice. It will be apparent, however, from an understanding of this disclosure that the present invention may be practiced in the production of stockings from other types of stocking blanks and that the stocking blank may be produced by means of separate conventional legger and footer knitting machines, or by means of conventional single unit straight knitting machines, and with or without a heeler knitting machine. The legger, footer and single unit machines, referred to, may be either single section machines for producing a single stocking blank at one time, or multi-section machines for simultaneously producing a number of stocking blanks.

To facilitate an understanding of this invention, Figures 3 through 10 show certain portions of a single unit full-fashioned hosiery knitting machine. This single unit machine may knit a substantially complete stocking blank including the foot portion of Figure 3 and then join the toe front edge portions 20, 21, 22 and 23 (see Figure 5) to provide the knitted seam 8 of Figure 2, all in a continuous operation. The illustrated conventional portions of a single unit, full-fashioned hosiery straight knitting machine comprise a take up roll 11, a loop supporting or needle bar 12 having a series of needles, and yarn carriers 13 and 14. These portions of the knitting machine cooperate in the usual manner to form knitted courses and wales, may perform their individual operations according to conventional practice and may be controlled and operated by conventional mechanism or other suitable means.

During the operations for knitting the foot of the stocking blank, all the needles of the bar 12 which support loops of the foot may serve as active or knitting needles. However, during the seaming operations to be described, it is preferable and desirable that only a few of the needles be operative for knitting and that the remainder be idle or inactive. The operative knitting or active needles for performing the seaming operation may be two in number (N1 and N2) as illustrated or more than two if desired. During the seaming operations, the needles at opposite sides of the needles N1 and N2 remain idle or inactive and serve to support toe edge loops prior to their being worked into the toe seam. Any suitable mechanism may be used for rendering needles N1 and N2 active or operative and the remaining needles of the bar 12 idle or inactive during the seaming operation.

For the purpose of transferring the loops in toe edge 10 in the course of the seaming operations, the knitting machine is provided with transfer devices 15 and 16. These devices 15 and 16 are similar in general character and operation to the transfer fingers or points of conventional knitting machines. However, in order to carry out the present method, either or both of the transfer devices 15 and 16 may be somewhat longer than those employed heretofore. That is, the transfer devices 15 and 16 may be provided with a greater number of conventional transfer points 17 than has, heretofore, been the practice. Each of these transfer devices 15 and 16 will require a number of points 17 corresponding to the largest number of loops it will transfer at any time in the seaming operation. In the illustrated form of this

invention, the largest number of loops to be transferred by the transfer device 16 in a seaming operation is substantially greater than the largest number of loops to be transferred by the transfer device 15. Therefore, the transfer device 16 is illustrated as having substantially more transfer points 17 than the transfer device 15.

It is to be understood that the transfer devices 15 and 16 may also be used in performing the usual transfer operations during the knitting of stocking blanks or portions thereof on the knitting machine. Any suitable means or mechanism may be used for operating and controlling the transfer devices 15 and 16 in the practice of this invention, as well as during their use for narrowing operations in the production of the stocking fabric.

During the seaming of the stocking toe, the transfer devices 15 and 16 preferably operate simultaneously. In all loops transfer operations, with the exceptions noted below, the transfer devices 15 and 16 move vertically to lift loops from inactive needles, travel a desired distance inwardly or toward each other with the lifted loops, and then have a downward movement to place each of the lifted loops on a needle spaced from the one on which it had been previously supported. By means of these transfer devices 15 and 16, the loops in each of the toe edge portions 20, 21, 22 and 23 are placed in succession on a particular active needle so that each edge loop will be interlooped with a loop of seaming yarn formed on the same active needle.

The yarn for seaming or joining the toe edge portion 20 to the toe edge portion 22 is fed by the yarn carrier 13, and the yarn for seaming the toe edge portion 21 to the toe edge portion 23 is supplied by the yarn carrier 14. These two yarns are preferably anchored in the toe fabric prior to the seaming operations. For this purpose, the first laid ends of the two seaming yarns may be bound into the stocking foot blank as the latter is being completed. For example, the yarn carriers 13 and 14 may begin operation several courses prior to the knitting of the last course in the stocking toe 6 and form what may be called tails 24 and 25 that are inter-knit with the adjacent loops of the stocking toe fabric. The area of these tails 24 and 25 is illustrated, for example, in dotted lines in Figure 6. These tails 24 and 25 may be composed of yarn formed into courses and wales and united to the toe fabric in a manner similar to conventional splicing or plating operations. The tails 24 and 25 may comprise two or more wales and be knit on a corresponding number of needles of the needle bar 12.

In the event the stocking toe 6 is provided with the conventional diamond points 5 as shown in the drawings, the tails 24 and 25 are preferably knit so that they extend along the center of the diamond points 5 (see Figure 6). Irrespective of whether the stocking blank is of the type having diamond points, the course of the tail 24, at the toe edge 10, is preferably knit on the needles which carry the adjacent end loops L10 and L11 of the toe edge portions 20 and 22. The course of the tail 25, at the toe edge 10, is preferably knit on the needles which carry the adjacent end loops L30 and L31 of the toe edge portions 23 and 21.

Except for the inter-knitting of tails 24 and 25 with the stocking toe fabric, the single-unit knitting machine, of which portions have been described, may proceed in the usual manner for knitting the stocking foot blank shown in Figures 75

3 and 5 until the last course of the blank (the one constituting toe edge 10) is formed, and the blank is in the position shown in Figures 3 and 5. The blank may now have the toe edge portions 20 to 23 united in accordance with this invention.

Heretofore, the practice, as previously explained, has been to continue the knitting operation beyond the toe edge 10 to provide a number of raveling courses (not shown). However, in the practice of this invention, the raveling courses may be, and preferably are, omitted.

The number of free or terminal wale loops at toe edge 10 varies with the size and style of stocking being knit. For the purposes of this description, the invention will be explained in connection with a toe edge 10 consisting of forty free terminal wale loops, L1 through L40. It will be understood, of course, that the toe edge 10 usually has more than forty free loops, and that the present method of providing the toe seam 8 may be substantially the same irrespective of the number of terminal wale loops in the toe edge 10. If the toe edge 10 has more than forty free loops, the method about to be described may be followed until all the edge loops are united in the toe seam 8.

To avoid confusion, only certain of the edge loops in the drawings are provided with reference numerals. The other toe edge loops, if numbered, would bear reference numerals in accordance with their position relative to loop L1 shown in Figure 5. For example, the second and third toe edge loops from the left end of toe edge 10 in Figure 5 are loops L2 and L3 respectively.

Each of the toe edge portions 20, 21, 22 and 23 preferably comprises the same number of loops. In the drawings, each of the toe edge portions 20, 21, 22 and 23 is shown as consisting of ten terminal wale loops. The drawings also show one of the diamond points 5 terminating in the terminal wale loops L10 and L11 at the adjacent ends of toe edge portions 20 and 22, and the other diamond point 5 terminating in the terminal wale loops L30 and L31 at the adjacent ends of toe edge portions 23 and 21. As illustrated in the drawings, the extremities of the diamond points 5 are usually so arranged in conventional full-fashioned hosiery that the number of terminal wale loops between their centers in the last course of stocking toe 6 is the same as the total number of terminal wale loops located beyond or outside of their centers in the same course. This arrangement of the diamond points 5 results in their extremities terminating at opposite ends of the completed toe seam 8 as shown in Figures 2 and 10.

It will be noted that in the drawings each of the toe edge portions 20, 21, 22 and 23 is arranged on the same number of needles, namely, ten. Loops designated as L1 through L40 are the loops formed to complete the last course of the stocking toe in usual manner. Loops U1 and U2, which are respectively supported on the same needles that hold loops L10 and L11, form the last course in the tail 24. Loops UU1 and UU2 compose the last course in the tail 25 and are held on the needles for loops L30 and L31. In Figures 5 through 10, the loops L1 through L40, which comprise the last course of the stocking blank toe 6, are represented by small half-circles. In the same figures, the loops formed from the seaming yarns of yarn carriers 13 and 14 are represented by the larger half-circles. The loops formed from the seaming yarn of the yarn carrier 13 compose the loop series U1, U2, etc., and

the loops formed of the seaming yarn from yarn carrier 14 compose the loop series UU1, UU2, etc.

An embodiment of this invention will now be described in which the toe edge portion 20 is joined to toe edge portion 22, and thereafter the toe edge portion 21 is joined to toe edge portion 23. It will be understood, however, that this order of operations may be reversed.

When the stocking blank has reached the stage of development shown in Figures 3 and 5, it is transferred from its position on the needle bar 12 illustrated by Figure 5 to the position illustrated by Figure 6. This transfer is to the right, as will be noted in the figures, and may be effected by the transfer devices 15 and 16 working as a unit. The transfer device 15 may be used to transfer the loops in the toe edge portion 20, including the tail loop U1, and the transfer device 16 may simultaneously transfer the remainder of the loops in the toe edge 10, that is the loops in toe edge portions 21, 22 and 23. This transfer operation is for the purpose of placing loops L10 and U1 on needle N1 and loops L11 and U2 on needle N2. These needles N1, N2 are preferably positioned in the center of the needle bar 12. By producing the entire toe seam on a few active needles at the center of the needle bar 12, a number of advantages are obtained. For example, the straight knitting machines now in use may be more readily adapted to perform the operations of this invention. The usual narrowing heads and narrowing control means of such knitting machines may be used for actuating the narrowing heads 15 and 16 in the seaming operations. The matter of rendering all needles inactive, except needles N1 and N2, during the knitting operation will also be facilitated. It will be understood, however, that the needles for knitting the toe seam may be positioned, if desired, at other places along the needle bar 12.

During the transfer represented by Figures 5 and 6, the yarn carriers 13 and 14 are preferably laterally shifted to the right with the transferred loops so as to avoid undue tension in the yarn extending between the carriers (13 and 14) and the tails 24 and 25. If the yarn carriers 13 and 14 are not so shifted, the loops in the tails 24 and 25 may become distorted, and a certain additional length of yarn may be pulled from the idle yarn carriers 13 and 14 by the stocking toe during its transfer. This additional length of yarn may result in imperfect knitting when the yarn carriers 13 and 14 are used subsequently in seaming or knitting operations.

With the stocking toe 6 and the illustrated machine parts having the relative arrangement shown in Figure 6, the yarn carrier 13 proceeds to lay yarn for a plurality or series of connected courses and wales. The yarn from carrier 13 when knitted will be a continuation of tail 24 and appear as a strip of narrow fabric. The courses are shown as formed on only two needles (N1 and N2), so that the yarn carrier 13 feeds yarn for only two wales. In these yarn laying operations, the yarn carrier 13 moves back and forth between the full line and dotted line positions of Figure 6.

The procedure for knitting the first course of the seam for toe edge sections 20 and 22 may be as follows: The yarn carrier 13 is shifted from the full line position to the dotted line position of Figure 6 to lay yarn along the needles N1 and N2. Conventional sinkers (not shown) sink the laid yarn and loop it about the needles N1 and N2 to form the loops of what may be termed the

"first course" of the seam being knit. The yarn of this "first course" is a continuation of the yarn in loops U1 and U2 which are a part of the so-called tail 24. The toe edge loops L10 and L11, and the tail loops U1 and U2 are now pressed off the needles N1 and N2 and interlooped with the loops of said "first course" in the manner conventional for knitting consecutive courses. Only the loops of said "first course" of seaming yarn 38 are now supported on the needles N1 and N2.

Transfer device 15 now lifts those loops of toe edge portion 20 that remain on the needles of the needle bar 12 and transfers them inwardly (that is to the right looking at Figure 6) a distance of one needle. That is, each loop is transferred from one needle to the next needle on its right in Figure 6. The toe edge loop L9 will thus be placed on needle N1. Simultaneously with the operation of the transfer device 15, the transfer device 16 lifts the remaining loops of toe edge portions 22, 23 and 21 including the tail loops UU1 and UU2 and transfers the lifted loops inwardly (that is, to the left, looking at Figure 6) a distance of one needle. This operation of the transfer device 16 places toe edge loop L12 on the needle N2. During this operation of the transfer device 16, the yarn carrier 14 is preferably shifted to the left a distance of one needle to maintain its close positioning relative to the tail 25 which it has knit.

This cycle of yarn laying, yarn looping, pressing off, loop transferring and yarn carrier shifting operations may be repeated a number of times until all of the loops in toe edge portion 20 have been transferred in succession to needle N1, all of the loops in toe edge portion 22 have been transferred in succession to needle N2, and the loops of both toe edge portions 20 and 22 have been interknitted with the courses and wales formed of seaming yarn from yarn carrier 13.

Thus in producing the "second course" of the seam for toe edge portions 20 and 22, the yarn carrier 13 is moved from the dotted line position to the full line position of Figure 6 to lay yarn along needles N1 and N2. This laid yarn is then looped by the sinkers (not shown) about the needles N1, N2 to form the loops of the "second course" of seaming yarn. The loops L9 and L12 and the loops of said "first course" of seaming yarn are next pressed off needles N1 and N2. The loops of the toe edge portions 20, 22, 23 and 21 remaining suspended on the idle needles of the needle bar 12 are then transferred inwardly a distance of one needle by the transfer devices 15 and 16 to place loops L8 and L13 on the needles N1 and N2 which still retain the loops of said "second course." The yarn carrier 14 is also shifted to the left (Figure 6) with the transfer device 16 for the reasons explained above.

It will also now be understood that the tenth course of seaming yarn is formed as follows: With the loops of the "ninth course" of seaming yarn and toe edge loops L1 and L20 suspended on needles N1 and N2, the yarn carrier 13 and sinkers (not shown) are operated for forming the "tenth course" of loops (U20 and U21) of the seaming yarn. The toe edge loops L1 and L20 and also the loop of the "ninth course" are next pressed off needles N1 and N2, leaving thereon the "tenth course of loops."

The relative arrangement of the stocking toe 6 and the machine parts is now as shown in Figure

7. The toe seam loops U20 and U21 forming the tenth course of the seaming yarn are supported by the needles N1 and N2. A seam 8 has been provided for the toe edge portions 20 and 21. The loops L21 through L40 of the toe edge portions 23 and 21, including the tail loops UU1 and UU2 are supported by what may here be termed idle or inactive needles at the right side (Figure 7) of the "knitting" or active needles N1 and N2.

To position the stocking toe 6 for the knitting operations to seam the toe edge portions 23 and 21, all the loops shown on the needles of needle bar 12 in Figure 7 are transferred to the left and placed on the needles as shown in Figure 8. The purpose of this transfer is to place the toe edge loop L30 and the tail loop UU1 on the knitting or active needle N1, and the toe edge loop L31 and the tail loop UU2 on the knitting or active needle N2. The yarn carriers 13 and 14 are also shifted to the left simultaneously with and to the same extent as the loops to which the yarn carrier seaming yarns are attached.

The transfer of loops from their position in Figure 7 to their position in Figure 8 may be secured by operation of the transfer devices 15 and 16. The transfer, if desired, may be effected by only the transfer device 16 providing, of course, the latter has as many transfer points 17 as there are needles supporting loops to be transferred.

After the transfer of loops to secure positioning of the stocking toe 6 on the needle bar 12 as indicated in Figure 8, the transfer devices 15 and 16 are shifted to occupy the position illustrated in Figure 8, so that they are ready to proceed in the following operations for joining toe edge portions 23 and 21.

The cycle of operations in forming each course 40 of a seam to unite the toe edge portions 23 and 21 is preferably the same as that explained above in forming each course for the seam 8 of toe edge portions 20 and 22. This cycle of operations may also be repeated until all of the loops in toe edge portions 23 and 21 have been interknitted with courses of the seaming yarn in substantially the manner described for seaming toe edge portions 20 and 22.

For example, the first cycle of operations following the stage illustrated in Figure 8 is as follows: The yarn carrier 14 is shifted from the full line position to the dotted line position of Figure 8 to lay its seaming yarn along the active needles N1 and N2. Conventional sinkers (not shown) sink the laid yarn and loop it about the needles N1 and N2 to form the "first course" of the seam for toe edge portions 23 and 21. The yarn of this "first course" is a continuation of the yarn in loops UU1 and UU2 which are a part of the so-called tail 25. The loops L30, L31, UU1, and UU2 are now pressed off simultaneously according to conventional pressing off practice, leaving only the loops of said "first course" of seaming yarn on the active needles N1 and N2. Transfer device 15 now lifts seaming yarn loops U20 and U21 and the loops L21 through L29 of toe edge portion 23 and transfers all the lifted loops inwardly (that is to the right in Figure 8) a distance of one needle. The toe edge loop L29 will thus be placed on needle N1. During the operation of the transfer device 15, the yarn carrier 13 is preferably shifted to the right (Figure 8) a distance of one needle to maintain its close positioning relative to the loops U20 and 75

U21 to which it is still connected by seaming yarn. Simultaneously with the operation of the transfer device 15, the transfer device 16 lifts the remaining loops of toe edge portion 21 (that is loops L32 through L40) and transfers these lifted loops inwardly (that is to the left in Figure 8) a distance of one needle. This operation of the transfer device 16 places the toe edge loop L32 on the active needle N2.

10 This cycle of yarn laying, yarn looping, pressing off, loop transferring and yarn carrier shifting operations is repeated until all of the loops in the toe edge portion 23 have been transferred in succession to needle N1, all of the loops in toe edge portion 21 have been transferred in succession to needle N2, and all the loops in toe edge portions 23 and 21 have been interknitted with the courses and wales formed of seaming yarn from yarn carrier 14.

15 After the last loops to be worked into the seam (that is loops L21 and L40) are interknitted with the seaming yarn of yarn carrier 14 and pressed off needles N1 and N2, the stocking toe 6, the needles of needle bar 12, and the yarn carriers 13 and 14 will have the relative arrangement illustrated by Figures 4 and 9. Loops UU20 and UU21, which are formed of yarn from yarn carrier 14 and constitute the last or tenth course of the seam for toe edge portions 23 and 21, are supported on active needles N1 and N2. Loops U20 and U21, which are formed of yarn from yarn carrier 13 and constitute the last or tenth course of the seam for toe edge portions 20 and 22, are supported on inactive needles n1 and n2.

20 The yarns from both yarn carriers 13 and 14 are now knit to form a tail 50 (see Figure 10). The purpose of this tail 50 is to avoid a run in the toe seam or seams 8 which have just been knit. This tail may be formed as follows. The loops U20 and U21 are transferred (as by means of the transfer device 15) to the right (looking at Figure 9) a distance of two needles. This transfer operation will place loop U20 on needle N1, which also supports loop UU20, and will place loop U21 on needle N2, which also supports loop UU21. During this transfer operation, the yarn carrier 13 is preferably shifted to the right (looking at Figure 9) a distance of two needles to place the same either in front or in the rear of yarn carrier 14 (see Figure 10). The two yarn carriers 13 and 14 may now move as in a conventional plating or splicing operation to lay simultaneously their two yarns for forming a plurality of connected courses, which may be 25 called a tail or a knitted narrow fabric end portion (50). This tail 50 comprises courses and wales with each course and wale containing throughout the same loops formed from the seaming yarn of both yarn carriers 13 and 14.

30 The stocking toe and its seam 8 will now appear as shown in Figures 2 and 10. When a sufficient number of courses (for example ten or twenty) have been provided for the tail 50, it is completely pressed off the needles N1 and N2 in the usual manner for pressing off operations when the knitting operation is finished.

35 The tail 50 is bound into the stocking in any suitable manner. It may, for example, be bound into the usual seam for sole portions 2. These sole portions 2 have selvage edges which according to conventional practice are seamed on a sewing machine (not shown).

40 When the toe seam has reached the stage indicated by Figure 9, the remainder of the process may be as follows: The yarn carrier 14 and the

needles N_1 and N_2 are used to knit a narrow strip of fabric to form a tail as a continuation of the seam for the toe edge portions 23 and 21. At the same time, the yarn carrier 13 and the needles n_1 and n_2 may likewise be used to knit a second narrow strip of fabric to form a tail as a continuation of the seam for the toe edge portions 20 and 22. These two separate tails (not shown) may then be removed from the needle bar 12, and bound into the stocking during its completion as explained with regard to tail 50. Each of the said two separate tails or narrow strips of knitted fabric may be formed of conventional courses and wales and a single continuous yarn.

Another procedure may be followed after the stocking toe seam has reached the Figure 9 stage. The two yarn carriers 13 and 14 may both lay their yarn along all the needles n_1 , n_2 , N_1 and N_2 in a series of course forming operations. This procedure will provide a tail having a width of four wales. Such tail will be composed of connected wales and courses, each with double loops throughout as in conventional plating or splicing practice. This tail may also be bound into the stocking during its completion.

Where needles, such as n_1 and n_2 are used in tail knitting operations, they become active needles for such purpose.

The relative loop arrangement in the toe seam formed as described above is illustrated diagrammatically by Figure 11, wherein loops L are toe edge loops or free terminal wale loops, and the loops U are seaming loops formed, for example, from yarn supplied by yarn carrier 13. It will be noted that each course of seaming loops U is interlooped with two toe edge loops L—one loop L from toe edge portion 20 and one loop L from toe edge portion 22. Another feature to be noted is that each of the two wales of the loops U extends lengthwise of the toe seam and is interlooped with the toe edge loops L of only one of the toe edge portions (20 or 22). Another characteristic of the illustrated seam loop structure is that there is a course of seaming loops U for each set of terminal wale loops L, a set of terminal wale loops consisting of a loop from each of the toe edge portions 20 and 22. This toe seam structure is relatively simple and avoids objectionable seam ridges, such as result in looping operations. The advantage in appearance and comfort secured by the improved seam is particularly desirable whether the wearer uses the open toe or closed toe style of shoe. The appearance will be pleasing to the wearer of open toe style shoes. The comfort secured by the absence of toe ridges will be pleasing to the wearer of the closed toe style of shoe.

The loop structure and arrangement in the seam for toe edge portions 23 and 21 is substantially the same as that illustrated in Figure 11.

By referring to Figure 11, it will be seen that each toe seam comprises narrow knitted fabric of seaming yarn formed into loops. These loops form regular courses and wales. Certain of the loops are formed on the needles N_1 and N_2 and are termed needle loops. Each two adjacent needle loops in a single course are connected by a sinker loop which is formed by a conventional sinker or divider of the usual straight knitting machine. In Figure 11, the needle loops are lettered U, and the sinker loops are lettered S. As shown in Figure 11, each course contains two needle loops U which are connected by a single sinker loop S. Figure 11 also shows the narrow

knitted strip of seaming yarn as having two wales of needle loops. When the toe pocket is completed as shown in Figure 2, the two toe seams, or the two halves of the toe seam, extend in end to end relation, and the needle loops of the seaming yarn in one seam will extend in a direction opposite to that of the needle loops of the seaming yarn in the other seam. The needle loops of seaming yarn in each seam will extend in a direction away from the diamond point at which such seam was started. This relative arrangement of seaming yarn needle loops in the two seams results from the knitting of the seams from the two diamond points to the center of the front toe edge.

The seaming yarns supplied by yarn carriers 13 and 14 may be and preferably are of the same weight, character, color and quality as the yarn from which the stocking toe fabric is knit. The seam 8 may consequently be inconspicuous or substantially the same in appearance as the adjacent toe fabric.

Where additional seam strength is desired, seaming yarn having a heavier weight than the yarn of the toe fabric may be used. A number of the important advantages of this invention will be secured when heavy seaming yarn is used. The seam will still be relatively flat and inconspicuous as compared with a seam formed by the usual looping machine.

Instead of knitting the seaming yarn to form only two wales as shown in Figure 11, the seaming yarn of each yarn carrier (13 and 14) may be knit to form a larger number of wales, for example, four. Where the seaming yarn is formed into courses having a width of four loops or wales, each of the two opposite outer wales may be interlooped or interknit with the loops in one toe edge portion. For example, considering Figure 11, the left outside wale would be interlooped with the loops of the toe edge portion 20, and the other outer wale (on the right) would be interlooped with the loops of toe edge portion 22. The two intermediate wales of the seaming yarn would then extend lengthwise of the seam and between the two rows of toe loops L of the toe edge portions 20 and 22.

The yarn carriers 13 and 14 in their yarn laying movements may be operated by conventional frictional driving mechanism. During their shifting movements with the transfer devices 15 and 16 as the latter transfer loops, the yarn carriers 13 and 14 may be controlled and shifted by any suitable mechanism, such as the mechanism (not shown) for operating the transfer devices 15 and 16.

It will be understood that the foregoing is illustrative, and that the invention includes all embodiments and modifications coming within the scope of the appended claims.

We claim:

1. In a method of seaming a knitted blank having an edge portion formed of a line of loops, the outer loops of said edge portion forming two spaced outer loop groups and the remaining loops thereof forming two adjacent inner loop groups, the steps of knitting yarn to form a plurality of connected courses while simultaneously interknitting therewith one of said outer loop groups and the inner loop group adjacent thereto, and thereafter knitting yarn to form a plurality of connected courses while simultaneously interknitting therewith the other of said outer loop groups and the other of said inner loop groups.

2. A method of seaming as recited in claim 1,

wherein each of the knitting steps includes the formation of the yarn into regular courses and wales, and the interknitting of the loop groups with said wales, but none of said wales for at least a substantial part thereof being interknit with more than one of the loop groups.

3. In a method of making hosiery, the steps of producing a toe blank having an edge formed of free terminal wale loops in four groups, anchoring at least two seaming yarns in said toe blank, knitting a plurality of courses from one of said yarns while simultaneously interknitting therewith the loops in two of said groups at one end of said edge to provide a seam for said two loop groups, and then knitting a plurality of courses from the other of said yarns while simultaneously interknitting therewith the loops in the other two of said loop groups to provide a seam therefor.

4. In a method of seaming a hosiery toe blank having two spaced diamond points and an edge portion formed of a line of free terminal wale loops extending between and beyond said diamond points, the free loops beyond said diamond points forming two spaced outer loop groups, and the free loops between said diamond points forming two inner loop groups, the steps comprising anchoring two seaming yarns in said toe blank, knitting a plurality of connected courses from one of said seaming yarns while simultaneously interknitting therewith one of said outer loop groups and the inner loop group adjacent thereto, and thereafter knitting a plurality of connected courses from the other of said seaming yarns while simultaneously interknitting therewith the other of said outer loop groups and the other of said inner loop groups.

5. In a method of seaming a hosiery toe blank having two spaced diamond points and an edge portion formed of a line of free terminal wale loops extending between and beyond said diamond points, the free loops beyond the centers of said diamond points forming two spaced outer loop groups, and the free loops between the centers of said diamond points forming two inner loop groups, the steps comprising anchoring a seaming yarn in each of said diamond points, knitting a plurality of connected courses from one of said seaming yarns while simultaneously interknitting therewith the outer and inner toe edge loop groups next to the diamond point in which said yarn is anchored, and thereafter knitting a plurality of connected courses from the other of said seaming yarns while simultaneously interknitting therewith the other of said outer and inner loop groups, whereby said free loops extending between said diamond point centers are seamed to free loops beyond the same.

6. A method of seaming knitted fabric having a continuous edge portion formed of a plurality of free terminal wale loops, said method comprising the steps of anchoring two seaming yarns in said fabric with the two yarns extending from spaced points in said edge portion and intermediate the opposite ends thereof, seaming together by means of one of said yarns adjacent groups of said loops lying at opposite sides thereof, and thereafter seaming together by means of the other of said yarns the adjacent groups of loops lying at opposite sides thereof.

7. A method as recited in claim 6 wherein each of said seaming steps includes the formation of the yarn into regular courses and wales, and the interknitting of the adjacent loop groups with said wales, but none of said wales for at least

5 a substantial part thereof being interknit with more than one of said loop groups.

8. In a method of knitting at least part of a full-fashioned stocking blank and a seam therefor on a straight series of needles, the steps comprising knitting stocking toe fabric on the needles with at least certain of the toe fabric wales terminating at an edge of said toe fabric in free loops, interknitting two seaming yarns with said stocking toe fabric during the formation thereof, seaming on said needles an outer group of said free loops to an adjacent inner group of said free loops with one of said seaming yarns, and thereafter seaming on said needles the opposite outer group of said free loops to the remaining inner group of said free loops with the other of said seaming yarns, whereby said toe fabric and the seams for said toe fabric edge are formed in a substantially continuous operation on said needles.

9. In a method of making hosiery, the steps of producing a hosiery blank with toe fabric having two spaced diamond points and an edge portion formed of free terminal wale loops extending between and beyond the centers of said diamond points, anchoring a seaming yarn in each of said diamond points, knitting a plurality of courses from one of said yarns while simultaneously interknitting therewith the free loops of said edge portion at one side of and beyond the center of the respective diamond point and free loops at and adjacent the other side thereof to form a seam, then knitting a plurality of courses from the other of said yarns while simultaneously interknitting therewith the free loops of said edge portion on either side of the center of the other of said diamond points to form a second seam, and finally knitting continuations of said two yarns to interknit said continuations and provide a tail extending from adjacent ends of said two seams.

10. A method of producing a seam for a line of terminal wale loops in an edge of knitted fabric, the terminal wale loops of said edge forming two outer loop groups and two inner loop groups, each of the four groups consisting of the same number of edge loops, the method to be performed on a straight series of needles including a set of active needles intermediate two sets of idle or inactive needles, said method comprising the steps of providing all of said terminal wale loops on said series of needles with the adjacent loops of one of said outer loop groups and of the adjoining inner loop group arranged on said set of active needles, and the remaining loops of said fabric edge on said two sets of idle needles, knitting yarn on said active needles to form a series of connected courses and simultaneously transferring inwardly the loops on both sets of said idle needles until all of the loops in said one outer loop group and said adjoining inner loop group have been placed on said active needles and interknit with said courses, then transferring all loops remaining on said needles in the same direction to place on said active needles the adjacent loops of the second of said outer loop groups and of the second inner loop group, knitting yarn on said active needles to form a second series of connected courses and simultaneously transferring inwardly the loops of said second outer loop group and said second inner loop group until all of the loops in said second outer loop group and said second inner loop group have been placed on said active needles and interknit with said second series of courses.

11. A method as recited in claim 10, wherein the yarn for each of said two series of courses is fed by a separate yarn carrier, an end of the yarn of each of said yarn carriers is interknitted with the knitted fabric prior to the knitting of the first series of connected courses, and the two yarn carriers are laterally shifted with the edge loops during said transfer of remaining loops in the same direction.

12. A method as recited in claim 10, wherein the yarn for each of said series of courses is fed by a separate yarn carrier, an end of the yarn of each of said yarn carriers is interknitted with the knitted fabric prior to the knitting of the first series of connected courses, each of the yarn carriers idles while the other yarn carrier is feeding thread in the course knitting operations, and the idling carrier is shifted with the loops in each transfer operation.

13. A method of producing a seam for a line of terminal wale loops in an edge of knitted fabric, the terminal wale loops of said edge forming two outer loop groups and two inner loop groups, each of the four groups consisting of the same number of edge loops, the method to be performed on a straight series of needles including a set of active needles intermediate two sets of idle or inactive needles, said method comprising the steps of providing all of said terminal wale loops on said series of needles with the adjacent loops of one of said outer loop groups and of the adjoining inner loop group arranged on said set of active needles, and the remaining loops of said fabric edge on said two sets of idle needles, knitting yarn on said active needles to form a series of connected courses and simultaneously transferring inwardly the loops on both sets of said idle needles until all of the loops in said one outer loop group and said adjoining inner loop group have been placed on said active needles and interknit with said courses, then transferring all loops remaining on said needles in the same direction to place on said active needles the adjacent loops of the second of said outer loop groups and of the second inner loop group, knitting yarn on said active needles to form a second series of connected courses and simultaneously transferring inwardly the loops of said second outer loop group and said second inner loop group until all of the loops in said second outer loop group and said second inner loop group have been placed on said active needles and interknit with said second series of courses, and knitting said yarns to form additional courses extending from said two series of courses.

14. A method for seaming a continuous line of free terminal wale loops forming an edge portion of knitted fabric, the terminal wale loops forming two inner loop groups extending between two outer loop groups, and the method to be performed with the aid of loop supporting means including a group of active needles, said method comprising the steps of knitting yarn on said active needles to form a series of courses, providing said edge loops on said loop supporting means, transferring the loops in one of said outer loop groups and the adjacent inner loop group onto said active needles, the loops in said last named outer loop group and said last named inner loop group being transferred in succession to said active needles and during the formation of said series of courses, whereby the loops in said outer loop group and the loops in said inner loop group are interknitted with and joined by said yarn, then knitting yarn on said active

needles to form a second series of courses, transferring the loops in the other outer loop group and the other inner loop group onto said active needles, the loops in each of said other loop groups being transferred in succession to said active needles and during the formation of said second series of courses, whereby said other loop groups are interknitted with and joined by said last named knitting yarn.

15. A method of producing a seam for knitted fabric having a continuous series of loops, the method to be performed on a needle bar having a group of active needles intermediate two spaced groups of inactive needles, said method comprising arranging said loops on the needles of the needle bar to provide each of said active needles with a loop and to provide loops on inactive needles at each side of the active needles, forming a series of connected courses by knitting yarn on said active needles, inwardly transferring said loops during the formation of said series of connected courses to interknit therewith loops transferred from both sides of said active needles, said knitting and transferring operations continuing until all of the loops on the inactive needles at one side of said active needles have been seamed to a substantially corresponding number of the loops transferred from the inactive needles at the other side of said active needles, then transferring all the loops remaining on the needles in the same direction to place loops on said active needles and on inactive needles of both of said two inactive groups, knitting yarn on said active needles to produce a second series of connected courses, and inwardly transferring said remaining loops onto said active needles until said remaining loops are all interknitted with said second series of connected courses.

16. A method of producing a seam for knitted fabric having an edge formed of a continuous line of free terminal wale loops, the method to be performed on a needle bar having a group of active needles intermediate two groups of inactive needles, said method comprising arranging said loops on the needles of the needle bar to provide a group of said loops on each of said two groups of inactive needles and the remaining loops on said active needles, one of said loop groups containing a larger number of loops than the other of said loop groups, forming a series of connected courses by knitting yarn on said active needles, inwardly transferring the loops of said two loop groups during the formation of said series of connected courses to interknit therewith loops of both of said loop groups, said knitting and transferring operations continuing until all of the loops in the smaller loop group and a corresponding number of loops in the larger loop group have been interknitted with said series of courses, then transferring all the loops remaining on said needles in the same direction to place said remaining loops on said active needles and on needles of both of said inactive groups, knitting yarn on said active needles to produce a second series of connected courses, and inwardly transferring said remaining loops of said inactive needles onto said active needles until said remaining loops are all interknitted with said second series of connected courses.

17. Knitted fabric having a knitted seam, the knitted fabric having outer edge portions folded inwardly and seamed to the intermediate edge portions, said edge portions being formed of loops, and said seam comprising knitted yarn having regular courses and wales with the wales

running lengthwise of said seam and interknit with said edge loops.

18. In knitted hosiery, a toe pocket comprising toe fabric having an edge formed of terminal wale loops, said toe fabric having the end portions of said edge folded inwardly, and knitted yarn joining the loops of said end portions to the other loops of said fabric edge, at least a substantial part of said knitted yarn having regular courses and wales with the wales parallel to said edge and interknit with said edge loops.

19. Knitted hosiery as recited in claim 18, wherein the knitted yarn comprises at least two wales, and one of said wales is interknit with loops in one of the folded end portions, and another of said wales is interknit with edge loops opposite the folded end portion loops.

20. Knitted fabric having a knitted seam, the knitted fabric having opposite outer edge portions folded inwardly and seamed to intermediate edge portions, said outer and intermediate edge portions being formed of loops, and the seam for said edge portions comprising narrow knitted fabric having regular courses extending across the width of the seam and regular wales running lengthwise thereof.

21. In knitted hosiery a toe pocket with opposite outer edge portions folded inwardly and seamed to intermediate edge portions, the seam for said edge portions comprising narrow knitted fabric having regular courses extending across the seam width and regular wales running lengthwise of the seam.

22. Knitted hosiery as recited in claim 21, wherein the toe edge portions are formed of loops, and the wales at opposite side edges of said narrow fabric are interknit with the edge loops lying at opposite sides of the seam.

23. Knitted hosiery as recited in claim 21, wherein the toe edge portions are formed of terminal wale loops, each edge loop is interlooped with an individual loop of the narrow fabric, and no wale of the narrow fabric is interknit with edge loops at opposite sides of the seam.

24. Full-fashioned hosiery having toe fabric formed of wales terminating in a course of loops at the end edge of the toe fabric, the opposite outer portions of said end edge being folded inwardly toward each other and seamed to the intermediate portion of said end edge, the seam for said end edge portions comprising narrow knitted fabric having courses extending across the seam width and wales running lengthwise of the seam, each loop in said end edge course of loops being interlooped with an individual loop of said narrow fabric, and no wale of the narrow fabric being interknit with edge loops at opposite sides of the seam.

25. A method for seaming knitted fabric, said fabric having an edge portion formed of a course of loops, the outer loops of said edge portion forming two spaced outer loop groups and the remaining loops thereof forming two inner loop groups, the method to be performed on a set of active needles intermediate two sets of inactive needles, said method comprising the steps of knitting yarn on said active needles to form a series of connected courses, providing one of said outer loop groups and the adjacent inner loop group on said needles with the adjacent end loops thereof arranged on said active needles and with the remainder of the loops in said last-named outer loop group and adjacent inner loop group arranged on said inactive needles and at

5 opposite sides of said active needles, transferring inwardly said loops on said inactive needles to said active needles, said loops on each of said sets of inactive needles being transferred in succession to said active needles and during the formation of said series of courses, whereby said last-named outer loop group and said last-named adjacent inner loop group are interknit with and joined by said yarn, then knitting yarn on said active needles to form a second series of connected courses, providing the loops of the other of said outer loop groups and the inner loop group adjacent thereto on said needles with the adjacent end loops thereof arranged on said active needles and with the remainder of the loops thereof on said inactive needles and at opposite sides of said active needles, transferring inwardly the loops on said inactive needles to said active needles, the loops on each of said sets of inactive needles being transferred in succession to said active needles and during the formation of said second series of courses, whereby said last-named outer loop group and the inner loop group adjacent thereto are interknit with and joined by said last-named knitting yarn.

26. In knitted hosiery, a toe pocket with each of the opposite outer toe front edge portions folded inwardly and seamed to an adjacent inner toe front edge portion, the seam for each of said outer edge portions and the adjacent inner edge portion being formed by a narrow knitted strip, each of the two seam strips being formed of needle and sinker loops arranged in regular courses and wales, the needle loops of said two seam strips extending lengthwise of the seams and in opposite directions.

27. A method for seaming a continuous front edge portion of the toe fabric of a stocking blank, said edge portion being formed of two outer groups of loops and two inner groups of loops, and the method to be performed with the aid of loop supporting means including a group of active needles, said method comprising the steps of knitting yarn on said active needles to form a series of connected courses, providing said edge loops on said loop supporting means, transferring the loops in one of said outer loop groups and the adjacent inner loop group onto said active needles, the loops in each of said two transferred groups being transferred in succession to said needles and during the formation of said series of courses, whereby the loops of said one outer loop group and said adjacent inner loop group are interknit with and joined by said yarn courses, then knitting yarn on said group of active needles to form a second series of connected courses, transferring the loops in the second of said outer loop groups and the second of said inner loop groups onto said active needles, the loops in each of said second outer loop group and said second inner loop group being transferred in succession to said active needles and during the formation of said second series of courses, whereby said second outer loop group and said second inner loop group are interknit with and joined by the yarn courses of said second series, said knitting yarn being knitted to form tails before and after being interknit with said edge loops, said tails to be anchored in the stocking toe for preventing a run in said knitted courses.

FRANK G. WEISBECKER.
